UNITED STATES PATENT OFFICE.

HERBERT J. WILLMOTT, OF UPTON, MASSACHUSETTS.

DESIGN FOR A DOLL.

Application filed June 7, 1926. Serial No. 17,969. Term of patent 14 years.

To all whom it may concern:

Be it known that I, HERBERT J. WILLMOTT, a citizen of the United States, and a resident of Upton, county of Worcester, State of Massachusetts, have invented a new, original, and ornamental Design for a Doll, of which the following description, in connection with the accompanying drawing, is a specification.

In the drawings:

Fig. 1 is a front perspective view of the doll constituting my new design; and Fig. 2 is a rear elevation thereof.

I claim:

The ornamental design for a doll as shown.

In testimony whereof, I have signed my name to this specification.

HERBERT J. WILLMOTT.
